C. B. BREMER & J. L. MOONEY.

SPARK INDICATOR,

APPLICATION FILED DEC. 30, 1912.

1,096,151.

Patented May 12, 1914.

Tätig. 1. Tätig. 2.

A technical drawing of a handle assembly. It features a central slot 16 and two side slots 15. The handle is shown in two views: a front view and a side view. The side view shows the handle's profile and the locations of the slots. The front view shows the handle's grip and the central slot 16.

UNITED STATES PATENT OFFICE.

CHARLES D. BREMER AND JOHN L. MOONEY, OF MILWAUKEE, WISCONSIN.

SPARK-INDICATOR.

1,096,151.

Specification of Letters Patent.

Patented May 12, 1914.

Application filed December 30, 1912. Serial No. 739,172.

To all whom it may concern:

Be it known that we, CHARLES D. BREMER and JOHN L. MOONEY, both citizens of the United States, and residents of Milwaukee, 5 in the county of Milwaukee and State of Wisconsin, have invented certain new and useful Improvements in Spark-Indicators; and we do hereby declare that the following is a full, clear, and exact description thereof.

Our invention consists in what is herein particularly set forth with reference to the accompanying drawings and pointed out in the claims of this specification, its object being to provide for simple, economical switch-controlled visible indication of the efficiency or non-efficiency of an electric sparking-circuit or circuits of internal-combustion engines, said invention being especially designed as a spark-indicator on an automobile 15 or motorcycle in view of the operator thereof.

Figure 1 of the drawings represents a front elevation of a switch-controlled indicator in accordance with our invention for 20 visibly determining the efficiency or non-efficiency of a plurality of electric sparking-circuits pertaining to a plural-cylinder internal-combustion engine; Fig. 2, a sectional view of the same indicated by line 2—2 in Fig. 1; Fig. 3, a side elevation of a similar indicator for a like purpose with relation to a single sparking-circuit of a single-cylinder internal combustion engine, and Fig. 4, a horizontal sectional view indicated by line 25 4—4 in Fig. 3.

Referring by numerals to Figs. 1 and 2 of the drawings 5 indicates a switch-board provided with a plurality of forwardly projecting blocks 6, each block being recessed 10 intermediate of its ends and having the recess therein open at the front. Engaging each block and extending into the recess thereof, to thus form a permanently visible 15 spark-gap, visible from the front, are pointed screw-posts 7. Secured between clamp-nuts 8, 9, on each post adjacent to the ends of the adjacent block, are contact-plates 10 of a knife-switch, and bound between the nuts 9 and other nuts 11, on said screws, are 20 wires 12, 13, of a sparking circuit, openings 25 for the wires being provided in the switch-board. The contact-blade 14 of each switch is pivotally connected to one of the contact-plates 10 of said switch, and the make or break of a circuit through the switch is effected by swinging said blade in or out of

frictional engagement with the other contact-plate of said switch. The several switch-blades may be connected by a bar 15 of insulating material, and a handle 16 60 may be employed in connection with the bar to facilitate a simultaneous operation of all the blades. The spark-gap in each of the aforesaid circuits is of greater current resistance than the switch in the same circuit. 65 Hence if the switches be closed, the spark-gaps are inoperative, but if said switches be open, the circuits will be completed through said spark-gaps to provide for visible indication of the good or poor sparking quality, 70 or the lack of spark in each circuit due to some interruption of the same or the weakness of a battery or batteries employed to generate the current.

In Figs. 3 and 4, a switch-board 17 is provided with a forwardly projecting concave-block 18, and engaging the block is a transparent cylindrical shell 19 having end-stoppers 20 of insulating material. Extending through the stoppers are pointed screw-posts 21 by which to form a spark-gap, and these posts also extend through conductor-plates 22 held by conductor screws 23 against the block 18 aforesaid. These screws are intercepted by other screws 24 80 engaging the same block and a notched switch-blade 25 is pivotal on one of the screws 24 to be swung in and out of contact with the other of the same screws. Opposing the plates 22 on the posts 21 are nuts 26, 85 and wires 27, 28 of a sparking-circuit are caught between said nuts and other nuts 29 on said posts. The spark-gap in the last described form of our indicator is of greater current resistance than the switch. Hence 90 if the switch be closed the spark-gap is inoperative, but said switch being open the circuit is completed through said spark-gap to provide for visible indication of the 95 sparking quality of said circuit or the lack 100 of spark due to conditions similar to those above noted.

The shell 19 serves to shield the points of the posts 21, and it is within the scope of our invention, as herein claimed, to glaze 105 the recesses of the switch-board blocks 6 to shield the points of the posts 6 above specified.

The first described form of our indicator is especially designed for the sparking-circuits of a plural cylinder internal combustion engine of an automobile, there being a 110

switch and spark-gap in each of said circuits. The other form of indicator is especially designed for inclusion in the sparking-circuit of a single cylinder internal-
5 combustion engine of a motorcycle.

The switch-board of either form of the indicator is permanently attachable by screws or otherwise to some portion of an automobile or of a motorcycle forward of
10 the driver of the vehicle, and in such position that the switch-blade or a handle common to two or more switch-blades of said indicator is within convenient reach of said driver facing the spark-gap or spark-gaps
15 aforesaid.

We claim:

1. The combination of a switch-board provided with spaced apart forward insulating projections, spark-gap posts extending through said switch-board projections into the space between the same, an electric-switch having contacts thereof in connection with the posts, and, terminal wires of an electric-circuit also connected to said posts,
20 the closed switch being of less resistance than the spark-gap.

2. The combination of a switch-board provided with a forwardly projecting insulating block having a front open recess be-

tween its ends, spark-gap posts in the block 30 extending into said recess of the same, an electric-switch having contacts thereof in connection with the posts, and, terminal wires of an electric-circuit also connected to said posts, the closed switch being of less re- 35 sistance than the spark-gap.

3. The combination of a switch-board provided with spaced apart insulating projections in pairs, spark-gap posts extending through each pair of said switch-board projections into the space between the same, electric-switches each having contacts in connection with a pair of the posts, terminal wires of an electric-circuit also connected to the same posts, and means in common with 40 all the switches for simultaneous opening and closing of the same, the closed switches being of less resistance than the spark-gaps.

In testimony that we claim the foregoing we have hereunto set our hands at Milwaukee in the county of Milwaukee and State of Wisconsin in the presence of two
50 witnesses.

CHAS. D. BREMER.
JOHN L. MOONEY.
